UNITED STATES PATENT OFFICE.

AUGUST ROCHWITE, OF WAUTOMA, WISCONSIN, ASSIGNOR OF ONE-HALF
TO W. R. HAMMOND, OF SAME PLACE.

DOOR-HANGER.

SPECIFICATION forming part of Letters Patent No. 611,395, dated September 27, 1898.

Application filed November 20, 1897. Serial No. 659,306. (No model.)

To all whom it may concern:

Be it known that I, AUGUST ROCHWITE, residing at Wautoma, in the county of Waushara and State of Wisconsin, have invented 5 a new and useful Door-Hanger, of which the following is a specification.

This invention relates to improvements in door-hangers; and the object of the same is to provide a hanger by means of which a 10 sliding door, when closed, may be swung into the door-opening and fit snugly against the jamb thereof, so as to render the door weather-tight.

With the above object in view the invention 15 consists of a track, roller-frames connected together and carrying rollers which move upon said track, crank-rods upon which the door is suspended, bent at right angles at their upper ends and pivotally connected to 20 the roller-frames and the door, and a rod connecting the bent ends of said crank-rods, so that they move in unison.

My invention further consists in the improved construction, arrangement, and combination of parts hereinafter fully described 25 and afterward specifically pointed out in the claim.

In order to enable others skilled in the art to which my invention most nearly appertains 30 to make and use the same, I will now proceed to describe its construction and operation, having reference to the accompanying drawings, forming part of this specification, in which—

35 Figure 1 is a perspective view of my invention, the door being shown open. Fig. 2 is a top plan view. Fig. 3 is a detail sectional view of one of the roller-frames and the crank-rod connecting the door thereto. Fig. 4 is an 40 end elevation of my improved hanger, the position of the crank-rods being shown in dotted lines when the door is swung outwardly from the door-opening. Fig. 5 is a detail sectional view of one of the securing 45 brackets and the lower end of the crank-rod. Fig. 6 is a detached perspective view of one of the roller-frames, brackets, and crank-rods.

Like letters of reference mark the same

parts wherever they occur in the various figures of the drawings. 50

Referring to the accompanying drawings, A designates a track which is secured to the partition above the door, as illustrated in Fig. 1, and B the roller-frames, in which the 55 rollers C are journaled, said rollers moving upon the track.

Brackets D are secured to the door adjacent its upper edge and provided with the upper and lower bearings E for the crank-rods F, which extend therethrough and are secured therein by nuts G upon their lower screw-threaded extremities. The upper vertical arms H of these crank-rods extend 60 through passages in the central webs I of the roller-frames, the upper ends of the crank-rods being bent angular, as illustrated, and connected by the rod J, which is pivoted thereto.

K is a stop and is designed to arrest the 70 movement of the door at the proper point to permit the latter to be swung into the door-opening.

When it is desired to open the door, the latter is swung outward, the crank-rods permitting such movement, when the door may be moved laterally upon the track. 75

By connecting the crank-rods they move simultaneously, so that the door may be swung outwardly from either edge, while a 80 rod L, connecting the roller-frames, prevents the spreading of the latter during the swinging of the door. Thus the swinging of the door is easily and readily effected, it being greatly facilitated by the above-mentioned 85 connection between the free ends of the crank-rods.

When it is desired to close the door, the same is moved laterally until the roller-frame comes in contact with the stops K, when the 90 door will swing into the door-opening and abut snugly against the jambs, thus rendering the door weather-tight.

By having the lower ends of the crank-rods screw-threaded either end of the door 95 can be readily raised should sagging of the same occur at any time.

From the above description it will be seen

that I have produced a door which when closed fits snugly against the jambs and which may be quickly and readily swung outward to permit lateral movement thereof and 5 also in which sagging is prevented.

While I have illustrated and described the best means now known to me for carrying out my invention, I do not wish to be understood as restricting myself to the exact de- 10 tails of construction shown and described, but hold that any slight changes or variations such as might suggest themselves to the ordinary mechanic will properly fall within the limit and scope of my invention.

Having thus fully described my invention, 15 what I claim as new, and desire to secure by Letters Patent of the United States, is—

In a door-hanger, the combination with a track, of carriers movable thereon, crank- 20 rods pivotally connected to said carriers and to the door and having their upper ends bent angular, and a rod pivotally connected to said angular ends, substantially as set forth.

A. ROCHWITE.
